UNITED STATES PATENT OFFICE.

RAIFORD WALKER DOUGLAS, OF MIAMI, FLORIDA.

AUXILIARY BOX-COVER.

1,141,699.

Specification of Letters Patent.

Patented June 1, 1915.

Application filed June 4, 1914. Serial No. 842,975.

To all whom it may concern:

Be it known that I, RAIFORD WALKER DOUGLAS, a citizen of the United States, residing at Miami, in the county of Dade and 5 State of Florida, have invented certain new and useful Improvements in Auxiliary Box-Covers; and I do declare the following to be a full, clear, and exact description of the invention, such as will enable others skilled 10 in the art to which it appertains to make and use the same.

This invention relates to improvements in display boxes and more particularly to devices for removably attaching an auxiliary 15 lid thereto.

The object of the invention is to provide simple and efficient means whereby an auxiliary lid or cover, preferably formed of transparent material, may be easily attached 20 to or detached from the body of a box, the improvement allowing convenient viewing of the contents of the box and protecting the contents from dust, moisture, etc., and permitting opening and closing of the box 25 to obtain access to the contents thereof whenever desired.

With this and other objects in view, the invention consists of certain novel features of construction, and the combination and 30 arrangement of parts as will be hereinafter described and claimed.

In the accompanying drawings: Figure 1 represents a side elevation of a cigar box with its permanent cover open and positioned to support the box at an inclination and with this improved attachment applied: Fig. 2 is a rear elevation thereof. Fig. 3 is a top plan view thereof: Fig. 4 is a longitudinal section of the rear portion of the 40 box taken on line 4-4 of Fig. 2 with the auxiliary lid in closed position. Fig. 5 is a similar view taken on the line 5-5 of Fig. 2. Fig. 6 is a side elevation thereof with the auxiliary lid partially open.

45 In the embodiment illustrated a box 1 is shown provided with the usual cover 2 here- in shown opened and disposed vertically downward to support the rear end of the box at an inclination for conveniently dis- 50 playing the contents thereof.

This improved auxiliary lid is here shown in the form of a frame 3 adapted to rest on the edges of the box and having a glass or other transparent sheet 4 mounted therein. At the rear end of this auxiliary cover is an 55 upwardly projecting card holder 5 which may be of any suitable or desired shape or construction. Secured to the rear edge of said auxiliary cover are depending box engaging clips 6 here shown substantially inverted U-shape in cross section and composed of resilient material to afford a gripping action on the box and cover 2 thereof when applied as is shown clearly in Fig. 2. These clips 6 have a hinge connection with 60 the auxiliary cover 4 as shown at 7 to permit said cover to be swung upward when desired for affording access to the interior of the box. A spring 8 of any desired construction here shown in the form of a leaf 70 spring is attached at one end to the rear face of the card holder 5 and spans the joint between the auxiliary cover and the box and has its free end positioned to bear against the rear wall of said box whereby its tension 75 is exerted for normally closing the cover 4, said spring being preferably outwardly bowed as shown in Fig. 2.

In the use of this invention the ordinary box cover 2 is first opened and swung downwardly into the position shown in the drawings and the auxiliary cover is then applied to the box by engaging the clips 6 thereof with the rear wall of the box, one of the legs of said clips extending inside the box 80 and engaging the inner face of its rear wall and the other leg extending over the open box cover 2 and engaging its exposed face whereby the auxiliary cover is reliably supported on the box. When in this position 85 the spring 8 carried by the card holder 5 will engage the exposed face of the box cover 2 and exert its tension to force the auxiliary cover into closed position so that when said cover is lifted to obtain access to the box it 90 will swing back in closed position immediately upon being released.

I claim as my invention:

An auxiliary box cover, a plurality of longitudinally spaced depending inverted U- 100

shaped clips hingedly connected therewith and composed of resilient material, said cover having an upright extension at its clip carrying edge, and a spring secured at one end to the rear face of said extension with its other end depending into position to engage the rear wall of a box when applied.

In testimony whereof I have hereunto set my hand in presence of two subscribing witnesses.

RAIFORD WALKER DOUGLAS.
